(57) **CLAIM**

The ornamental design for a clasp assembly, as shown and described.

DESCRIPTION

FIG. 1 is a front perspective view of a first embodiment of our new and ornamental design for a clasp assembly, showing the first embodiment of the clasp assembly in a clasped position;

FIG. 2 is a back perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front elevation view thereof, showing the first embodiment of the clasp assembly in an alternate, unclasped position;

FIG. 10 is a back elevation view thereof;

FIG. 11 is a top plan view thereof;

FIG. 12 is a bottom plan view thereof;

FIG. 13 is a front view of the first embodiment of the clasp assembly, showing the first embodiment of the clasp assembly in the clasped position and in use between two cups of a brassiere;

FIG. 14 is a front view of the first embodiment of the clasp assembly, showing the first embodiment of the clasp assembly in the clasped position and in use between a strap and a wing of the brassiere; and

FIG. 15 is a front perspective view of a second embodiment of the clasp assembly, the only difference from the first embodiment being that the second embodiment has break lines to indicate that any portions that are not shown form no part of the claimed design; and,

FIG. 16 is a rear perspective view thereof.

In FIGS. 13 and 14, the broken lines depict environmental subject matter; the broken lines and the subject matter they

(Continued)

depict form no part of the claimed design. In FIGS. 15 and 16, the pairs of break lines in the drawings of the second embodiment of the clasp assembly indicate that any portion of the clasp assembly between the break lines forms no part of the claimed design. All other views of the second embodiment of the clasp assembly are the same as those shown in FIGS. 3-14, with the exception that the second embodiment of the clasp assembly makes no claim of portions between the locations of the break lines in FIGS. 15 and 16.
